UNITED STATES PATENT OFFICE.

KENNETH D. BRYSON, OF MADISON, NEW HAMPSHIRE.

FOUNTAIN-PEN BLOTTER.

1,170,955.

Specification of Letters Patent.

Patented Feb. 8, 1916.

Application filed January 9, 1915. Serial No. 1,347.

To all whom it may concern:

Be it known that I, KENNETH D. BRYSON, a citizen of the United States, residing at Madison, in the county of Carroll and State of New Hampshire, have invented certain new and useful Improvements in Fountain-Pen Blotters, of which the following is a specification.

This invention relates to writing pens, particularly to fountain pens, and has for its object the provision of a blotting device associated with a fountain pen cap and normally disposed entirely therin and readily extensible therefrom into a position in which it may be contacted with and rolled upon the surface to be blotted.

An important object is the provision of a rotary blotting device of this character so constructed that when it is extended from the cap into its operative position the blotting member will automatically move into a position at an angle in relation to the pen whereby blotting may be easily accomplished without danger of touching the pen point or the hand against the surface of the paper, or the like, written upon.

A further object is the provision of a device of this character so constructed that the absorbent material of the blotting member may be readily removed and replaced or washed.

With these and other objects and advantages in view such as cheapness in manufacture, efficiency and durability in service, ease of operation, and the general improvement of the art, the invention consists in the novel construction and arrangement of parts to be hereinafter more fully described and illustrated in the accompanying drawings, in which: Figure 1 is an elevation of a fountain pen having a cap thereon equipped with the blotting device, Fig. 2 is an enlarged sectional view through the cap and blotting device showing the blotting member in its operative position, Fig. 3 is a similar view showing the blotting member in its inoperative position disposed within the cap, Fig. 4 is a cross sectional view on the line 4—4 of Fig. 3, Fig. 5 is a view similar to Fig. 2 showing a different form of spring and mounting for the blotting member, and Fig. 6 is a perspective view of the spring shown in Fig. 5 removed.

Referring more particularly to the drawings, the numeral 1 designates a fountain pen having a cap 2 thereon of the ordinary

design except that it has both ends open. Slidably disposed within the cap 2 is a shield 3 closed at its outer end as shown at 4 and provided with an opening in one side 60 extending about half its periphery. A knob 5 is provided on the closed end 4 whereby the shield may be readily moved. The shield 3 is prevented from withdrawal entirely out of the cap 2 and also prevented from rotation therein by means of a projecting tine 6 disposed within a longitudinal groove 7 formed in the inner wall of the cap 2. An annular rib 8 is formed on the inner wall of the shield 3 intermediate its ends and 70 nearer its open end for a purpose to be described.

The blotting member is designated as a whole by the numeral 9 and comprises a cylindrical shell 10 covered with a cylinder 75 of absorbent material 11 which may be blotting paper, wash leather or any other suitable substance. This blotting member is supported within the shield 3 by means of a leaf spring 12 having one end secured 80 upon the closed end 4 of the shield and having its other end secured upon a guide sleeve 13 disposed within the shell 10 and serving as a bearing about which the shell may be rotated. When the blotting device is not 85 in use, the blotting member 9 is disposed within the shield 3 and the shield 3 is disposed entirely within the cap 2, the tine 6 engaging the farther end of the groove 7 for preventing too great inward movement 90 of the shield. This position is shown in Fig. 3. In this position, the blotting member 9 is itself prevented from inward movement by the rib 8. When it is desired to use the blotting device, the operator grasps 95 the knob 5 and pulls the shield 3 out of the cap 2 until the tine 6 engages the other end of the groove 7. When this point is reached, the blotting member 9 will slip off the end of the cap 2 under the influence of 100 the spring 12 and will be disposed as shown in Figs. 1 and 2. The spring 12 is so arranged that it will hold the blotting member in such a position that its end will be inwardly of the edge of the cap 2, thus preventing the blotting member from sliding off from the sleeve 13. In blotting, the pen 1 is held by the operator so that the blotting member 9 will be disposed flat upon the surface to be blotted, the pen extending in an 110 inclined direction as shown in Fig. 1, thus preventing accidental contact of the pen or

the hand with the paper or the like. Then by moving the pen 1 back and forth the blotting member 9 will roll over the surface to be blotted, as the shell 10 is freely 5 revoluble upon the guide sleeve 13. To return the blotting device to its original position it is merely necessary that the operator grasp the shield 3 and blotting member 9 with his thumb and forefinger to press the 10 blotting member into the shield against the resistance of the spring 12, and then push the shield 3 into the cap 2. When the absorbent material 11 becomes too greatly soiled, the blotting member may be removed 15 by grasping its free end and pulling it outwardly free of the edge of the cap 2 and then pulling it longitudinally to slide it off from the guide sleeve 13. The absorbent material 11 may then be readily removed 20 and replaced.

In Figs. 5 and 6 I have shown a slightly modified form of the invention. In this form instead of using the spring 12 secured upon the end 4 of the shield 3 I provide a 25 spring 14 which has one end 15 secured to the inner wall of the shield 3 adjacent the opening therein and its other end 16 bent over and apertured for the reception of a pin 17 threaded through the closed end 4 30 of the shield 3 and having a knob 18 on its outer end. The spring 14 has oppositely extending arms 19 formed thereon and bent upwardly, as shown, to form bands serving as guides for revolvably supporting the blotting member 9. The operation of this form of the invention is the same as that of the preceding form. In order to remove the blotting member 9 in this second form, it is necessary to unscrew the pin 17 sufficiently 35 40 far that its end will be disengaged from the apertured end 16 of the spring 14, whereupon the outer end of the blotting member will drop down permitting its removal.

From the foregoing description and a 45 study of the drawings it will be apparent that I have thus provided a simple, efficient and easily operated blotting device for fountain pens which will be normally concealed from view and protected by the cap and 50 which may be quickly extended into its operative position for blotting. It will be noted that by forming the blotting cylinder hollow, the point of the pen may pass freely far into the cap when the cap is removed 55 from the butt end of the pen and placed over the writing end of the pen as a protector.

Having thus described my invention what I claim is:

60 1. The combination with a fountain pen cap of a blotting device comprising a shield

slidable within the cap, a cylindrical shell disposed within said shield and covered with absorbent material, and a spring normally forcing said cylindrical shell outwardly 65 through an opening in said shield when said shield is pulled partially out of said cap.

2. The combination with a fountain pen cap of a blotting device comprising a shield slidable longitudinally within the cap and 70 provided in its periphery with an opening, a spring connected with the outer end of said shield and carrying a guide upon its other end, and a cylindrical shell revoluble upon said guide and covered with absorbent material, said spring forcing said shell outwardly 75 through said opening when said shield is pulled out of said cap, said shell being then disposed with its axis at an angle to the axis of said cap.

3. The combination with a fountain pen cap of a blotting device comprising a cylindrical shield slidable longitudinally within said cap and provided in its periphery with an opening, a tine on said shield disposed within a groove on the inner periphery of said cap for preventing excessive longitudinal movement of said shield, a rib formed on the inner periphery of said shield adjacent said opening, a leaf spring connected 80 with the outer end of said shield, a guide carried by said spring, and a cylindrical shell revoluble upon said guide and covered with absorbent material, said spring forcing said shell outwardly through said opening 85 when said shield is pulled partly out of said cap, the edge of said cap preventing longitudinal displacement of said shell when in its outer position, and said rib preventing longitudinal displacement of said shell when 90 in its inner position within said shield.

4. The combination with a fountain pen cap having both ends open, of a blotting device comprising a cylindrical shield slidable longitudinally within said cap, a pin 105 threaded through the outer end of said shield, a spring having one end engaging the inner periphery of said shield adjacent said opening and its other end apertured for engagement with said pin, guide bands 110 formed on said spring, and a cylindrical shell revoluble upon said guide bands and covered with absorbent material, said spring forcing said cylindrical shell outwardly 115 through said opening when said shield is pulled partly out of said cap.

In testimony whereof I hereto affix my signature in the presence of two witnesses.

KENNETH D. BRYSON.
